CLAIM

The ornamental design for a electric line conditioner, as shown and described.

DESCRIPTION

FIG. 1 is a front top side perspective view of the electric line conditioner showing my new design;

FIG. 2 is a top plan view thereof;

FIG. 3 is a left side elevational view thereof;

FIG. 4 is a right side view thereof;

FIG. 5 is a front elevational view thereof;

FIG. 6 is a back elevational view; and,

FIG. 7 is a perspective view thereof, shown in its environmental use.

The broken lines depicting environmental structure are for illustrative purposes only and form no part of the claimed design.

The broken line(s) which define the bounds of the claimed design form no part thereof.
